Primary Examiner — Dana K Weiland*Assistant Examiner* — Kathryn Elizabeth Zieno(57) **CLAIM**

The ornamental design for a module for shower system, as shown and described.

DESCRIPTION

FIG. 1 is a perspective view of a module for shower system showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the module for shower system where the module for shower system is in a configuration of use.

The broken lines in FIG. 9 depict environment and form no part of the claimed design. The other broken lines in the drawings depict portions of the module for shower system that form no part of the claimed design.

1 Claim, 9 Drawing Sheets(56)
